United States Patent Office

Des. 187,851
Patented May 3, 1960

187,851

HARD SURFACE FLOOR COVERING OR SIMILAR ARTICLE

Murray E. Fleender, Astoria, N.Y., and Peter Zevas,
Irvington, N.J., assignors to Congoleum-Nairn Inc.,
Kearny, N.J., a corporation of New York

Application March 9, 1959, Serial No. 54,900

Term of patent 14 years

(Cl. D92—17)

Fig. 2

Fig. 1 is a plan view of a hard surface floor covering or similar article showing a full repeating unit between the outermost horizontal and vertical dashed lines; and

Fig. 2 is an enlarged view of a portion of a repeating unit of the hard surface floor covering or similar article shown in Fig. 1.

We claim:

The ornamental design for a hard surface floor covering or similar article, substantially as shown and described.
